(57) **CLAIM**

We claim the ornamental design for input pen with light, as shown and described.

DESCRIPTION

FIG. 1 is a front/top/right-side perspective view of an input pen with light showing our new design;

FIG. 2 is a front/top/right-side perspective view thereof with a right-side, cap portion removed and a right-side pin portion in a condition of use;

FIG. 3 is a front elevational view thereof as shown in FIG. 1, the opposite, rear elevational view being a mirror image and, therefore, not shown;

FIG. 4 is a top plan view thereof as shown in FIG. 1;

FIG. 5 is a bottom plan view thereof as shown in FIG. 1; FIG. 6 is a left-side elevational view thereof as shown in FIG. 1;

FIG. 7 is a right-side elevational view thereof as shown in FIG. 1; and,

FIG. 8 is a top plan view thereof with the right-side, cap portion removed and the pin portion a condition of storage, the bottom plan and front and rear elevational views being mirror images and, therefore, not shown, the right-side elevational view being disclaimed to the extent not shown and, therefore, not shown; and,

FIG. 9 is a top plan view thereof as shown in FIG. 2.
